C. P. SHINDLER

DOOR LOCKING DEVICE

Filed May 29, 1923

INVENTOR
CHRISTIAN PHILIP SHINDLER
By *James Taylor* *Atty.*

UNITED STATES PATENT OFFICE.

CHRISTIAN PHILIP SHINDLER, OF VANCOUVER, BRITISH COLUMBIA, CANADA.

DOOR-LOCKING DEVICE.

Application filed May 29, 1923. Serial No. 642,242.

To all whom it may concern:

Be it known that I, CHRISTIAN PHILIP SHINDLER, a subject of the King of Great Britain, and a resident of the city of Vancouver, in the Province of British Columbia, Canada, have invented certain new and useful Improvements in Door-Locking Devices, of which the following is a specification.

My invention relates to improvements in door locking devices, of the kind known as combination locks, and the object of my invention is to provide a device of this nature which is of simple, strong, and practical construction, capable of a wide range of different combinations and easily manipulated by the one having knowledge of its operation while at the same time it may with great facility be rendered temporarily inoperative so as to be incapable of use by any unauthorized person to open any door to which it is applied.

I attain this object by the construction illustrated in the accompanying drawings in which—

Fig. 1 is a side view of the knob and spindle of the lock, in outside elevation.

Fig. 2 is a sectional view of the knob, taken through the longitudinal centre line of Fig. 1, the knob being free of the spindle.

Fig. 3 is a sectional view of the knob similar to Fig. 2, the knob being engaged to the spindle.

Fig. 4 is an end view of the knob with end cap removed.

Fig. 5 is a detail view of the spindle.

Fig. 6 is a view of the knob cap looking on the inside.

Fig. 7 is a detail view, in perspective, of the knob spring.

Fig. 8 is a detail view, in perspective, of the knob and spindle connecting plug.

Fig. 9 is an enlarged detail view, in perspective of the disc spring.

Fig. 10 is a detail view, in perspective, of the knob and spindle connecting plug follower.

Fig. 11 is an end view of the spindle.

Fig. 12 is a detail view of a combination disc.

Fig. 13 is a plan view, in part section, of a portion of a door fitted with the lock bolt.

Similar figures of reference indicate similar parts throughout the several views.

The combination lock resides in the knob, indicated generally by the numeral 1, and this knob is in two parts, the inner part 2

being rotatably mounted on the spindle 3 and the outer part 4 being in the form of a cap which is detachably secured to the part 2 by suitable screws 5 and covers the combination assembly to be described.

The part 2 is annular and, with the cap, is of dimensions for convenient gripping by hand and on one side, the cap side, it is provided with an annular recess 6 in which the combination discs, hereinafter described, are seated while from its opposite side extends a concentric extension 7 having a bore 8 through which the spindle 3 freely extends, which bore, from a point within a short distance from the outer end of the extension 7 to the recess, is enlarged in diameter as at 9 to receive rotatably a barrel 10 secured to the spindle by a screw 10^a, ball races 11 and 12 being inserted between the barrel and the wall of the enlarged bore 9 to eliminate friction as far as possible. The barrel 10 may be longitudinally adjusted on the spindle by loosening the screw 10^a and is larger in diameter than the thickness of the spindle, which is of the usual square section, so that a shoulder is formed at 13, as shown in Fig. 5, against which shoulder the shoulder 14 in the part 2 formed by the enlargement of the bore 8 abuts when the parts are assembled together, the abutting of the two shoulders 13 and 14 preventing the knob from being withdrawn from the outer end of the spindle. 15 indicates a square recess formed in the knob end of the spindle, and 16 indicates a key removably fitted in a dovetail seat 17 formed in the spindle on one side parallel to its longitudinal axis, which key is capable of being removed from its seat 17 and inserted in a similar seat 18 formed in the spindle on the side opposite to seat 17 but is cut at an angle of approximately 30 degrees to it.

The cap 4 is also formed annular and is complementary to the part 2, being recessed annularly around the edge 19 as at 20 to fit snugly around an annular ridge 21 formed on the part 2, as shown in Figs. 2 and 3, and it is detachably secured to the part 2 by the screws 5 which pass through the part 2 from its inner side, that is, the side next the door, and are screwed into threaded holes 22 provided in a stiffening portion 23 formed integrally on the inside of the cap. Extending transversely of the cap and cut in the stiffening portion is a slot 24 of a width designed to receive freely

a spring 25, which spring is shown in detail in Fig. 7, this slot being enlarged at mid-width to form a four-sided recess 26, and the depth of the slot and of the recess is substantially the depth of the stiffening portion, which extends from the inside of the end wall of the cap to within a short distance of the recess 20. The spring 25 is seated in the slot 24 and is provided at mid-length with a short flattened portion 27 apertured as at 28, being extended on one side of this portion in U-shaped form, as at 29, while on its opposite side it is first curved outwardly, as at 30, then reversely 10 bent into U form, as at 31, and then doubled over, as at 32, being finally carried along horizontally as at 33 for a short distance inwardly in the same plane as the flattened portion 27, and within the space 34 15 formed by the doubled over portion 32 is inserted a small coil spring 35.

36 indicates a square sided plug adapted to engage slidably the square recess 15 in the end of the spindle 3 and also the recess 26 in the cap, which plug is provided in its outer end with a threaded hole 37 into which is secured a screw 38 passed through the aperture 28 of the portion 27 of the spring 25 and thus connect the spring and the plug 20 together. From one side of the plug extends a square section arm 39 which is bent inwardly at right angles to form an extension member or arm 40 which arm 40 projects through a slotted aperture 41 25 formed in the part 2 and is laterally movable therein, this arm being threaded on its outer end as at 43 and provided with a button 44, which is screwed on to the thread 43 exteriorly of the part 2, as shown in Figs. 2 and 3. 45 indicates a notch formed in the member 40 intermediate its length in which the free end of the U-shaped portion 29 of the spring 25 is engaged when the device 30 is assembled.

46 indicates a follower for the plug 36 consisting of a V-shaped member adapted to fit the two sides of the plug opposite from the member 40 and having an integral pin 47 extending slidably through an aperture 48 formed in the cap 4, this pin being provided on its outer end and exteriorly of the cap with a button 49 similar to the button 44 of the member 40.

The combination discs are, in the device 55 illustrated, three in number and they are formed similar to the disc 50 shown in Fig. 11, their diameter being such that they fit snugly the recess 6 when inserted therein one on the other, each disc being in the 60 form of a washer in the outer periphery of which are cut three spaced notches 51 each of a size to allow the arm 40 to fit therein while from its inner periphery project inwardly a series of projections 52 spaced 65 apart at varying distances. The thickness

of the discs is such that when placed in the recess, with a thin washer between each of them, as indicated by the numeral 53 in Figs. 2 and 3, to reduce friction between the discs, the outermost disc does not project 70 out of the recess, and a side pressure is maintained on the edge of the discs by means of a small leaf spring 54 seated in a recess 55 cut in the wall of the recess 6 and secured at one end as at 56, this spring 75 being in the form of three spring fingers 71, 72, and 73, as shown in Fig. 9 each bearing on one disc so that a pressure is assured on all the discs.

The outer periphery of the extension 7 is graduated at its outer end as indicated by the numeral 57, the graduations being preferably in the form of lines representing different numbers, one line indicating the number 1, two lines 2, three lines 3 and so on and between the respective numbers are formed small knobs 58, the purpose of which is to assist in forming the operating combination in the dark by the feel of the knobs. The graduation marks are read in conjunction with a central mark 59 on the escutcheon plate, indicated by the numeral 60 in Fig. 13. Any other graduated arrangement may be used, however, as may be desired.

The locking device may be used with any form of lock, a preferred form being that indicated in Fig. 13, in which 61 indicates the locking bolt slidable in a tube 62 insertible into a hole 63 bored in the edge of the door, which bolt is provided with a jaw 64 in which is seated for partial rotation a pawl 65 engageable when turned in either direction with a right angle lug 66 formed on the jaw to retract the bolt, the pawl 105 being operated by the spindle 3 which extends through it from side to side of the door and on the inside of the door the spindles is fitted with an ordinary door knob 67 while on its outer side the combination locking knob described in the foregoing is fitted. The bolt 61 is projected by means of a spring 68 extending between a shoulder 69 on the bolt and a shoulder 70 on the tube 62 respectively.

The manner in which the combination locking device is assembled and its operation may be briefly described. The parts being disassembled, to put them together the part 2 is placed on the spindle 3 so that the barrel 10 and ball races 11 and 12 are seated in the enlarged bore 9, the square portion of the spindle then extending freely through the bore 8 and the end portion of the barrel 10 carrying the key 16 projecting into the recess 6. The combination discs 50 are then placed in the recess one on the other with a washer 53 between each of them and it will be seen that the end of the barrel 10 also projects through the as- 130

sembled discs and that the key 16 will contact with one or other of the projections 52 when turned in either direction. The spring 25 is attached to the plug 36 by the screw 58 and the free end of the spring portion 29 is seated in the notch 45 of the arm 40, the spring and plug being then placed in the cap slot 24 and recess 26, as also is the follower 46 the pin 47 of which is inserted 10 through the hole 48 of the cap, this pin being disposed under the horizontal portion 33 of the spring 25 which exerts a spring pressure on the pin, this spring pressure being assisted by the small coil spring 34, which is under compression when in place. The cap is now placed on the part 2 and secured to it by the screws 5, and, referring now to Fig. 2, it will be seen that the arm 40 is disposed in the slotted aperture 41 and that the plug 36 is resting on the end of the spindle on one side of the recess 15 its arm 40 being clear of the combination disc notches 51, consequently the spring 25 is under compression tending to force the 20 plug downwardly when the parts are in the position shown in Fig. 2 and as just described. It should be noted here that the length of the recess 26 in the cap is such as will permit lateral movement therein of the plug 36 and follower 46 sufficient to bring the plug into alignment with the recess 15 and that the spring 25, while tending to force the plug downwardly also tends to move both it and the follower laterally in 30 either direction according as the combination is arranged or disarranged.

It has already been stated that the combination discs are under a slight side pressure due to the spring 54, but this pressure is not sufficient to prevent free turning of the knob when hand pressure is exerted thereon sufficient to overcome that of the spring 54 and thus when the arrangement of the parts is as shown in Fig. 2 the knob may be rotated 40 freely without actuating the spindle, thus giving the impression to anyone attempting to open the door without authority and without knowledge of the operation that the lock is broken or out of order, the discs in that 45 event being held stationary by the engagement of their projections 52 with the key 16 while the part 2 moves around them.

The side pressure on the discs due to spring 54, however, is such that when the knob is partially rotated slowly, as when making the combination, the discs will move with the part 2 and thus, if the discs are arranged so that it is known that, the knob being turned first in one direction, a projection 52 of the first disc will contact with the key 16 when the graduation 3 is aligned with the mark 59 on the escutcheon plate, that a projection 52 of the second disc will contact with the key 16 when the graduation 65 6 registers with the mark 59 the knob being

turned in the opposite direction, and that a projection 52 of the third disc will contact with the key when the graduation 1 registers with the mark 59, then to use a combination of 3—6—1 the knob is first turned to 3, then 70 back to 6, and back again to 1. When this is done the slots of one set of outer peripheral slots 51 in the discs are in registration one with the other and with the aperture 41 so that the arm 40 is moved thereinto under 75 the influence of the side action of the spring 25 thus bringing the plug 36 directly into alignment with the recess 15 of the spindle 3 into which it is moved by the downward action of the spring so that the knob and 80 spindle are then operatively connected together, enabling the lock bolt to be retracted in the usual manner. The parts are then as shown in Fig. 3 from which it will be seen that the button end of the arm 40 projects beyond the inner face of part 2 so that to render the device inoperative and allow the combination to be disarranged all that is necessary is to press the arm 40 inwardly 85 by the fingers to disengage the plug 36 from the recess 15, whereupon it is moved out of alignment with the recess by the spring 25 and held out of engagement therewith until the combination is again made as described in the foregoing, the knob being spun a few 90 times to throw the disc slots out of registration.

Different combinations may be made by rearranging the discs differently so as to allow more or less travel of the key between 100 the respective disc projections and also by changing the key 16 from the slot 17 to the 30 degree slot 18 but it is not necessary to describe this in detail as the action and operation of the parts is the same as has just 105 been described.

What I claim as my invention is:—

1. A door locking device comprising, a knob divided into an inner part and an outer part detachably connected together, said inner and outer parts having a concentric annular recess and a transverse slot in their inner faces respectively, a plurality of discs mounted in said annular recess in frictional contact with the wall thereof 110 each having an outer peripheral notch and a plurality of unequally spaced inner peripheral projections, a spindle on which said knob is rotatably mounted recessed in its inner end and extending at its inner end 115 through said annular recess and said discs, a key carried by said spindle with which predetermined disc projections contact when the knob is moved in opposite directions alternately whereby the disc notches are 120 brought into alignment one with the other, and a plug carried by the outer part slot engageable in the spindle recess on the aligning of the disc notches.

2. A door locking device comprising, a 125

knob divided into an inner part and an outer part detachably connected together, said inner and outer parts having a concentric annular recess and a transverse slot 5 in their inner faces respectively, a plurality of discs mounted in said annular recess in frictional contact with the wall thereof each having an outer peripheral notch and a plurality of unequally spaced inner peripheral 10 projections, a spindle on which said knob is rotatably mounted recessed in its inner end and extending at its inner end through said annular recess and said discs, a key carried by said spindle with which predetermined disc 15 projections contact when the knob is moved in opposite directions alternately whereby the disc notches are brought into alignment one with the other and with the inner part slotted aperture, a plug carried in the outer part slot out of alignment with the spindle recess having an arm extending through the inner part slotted aperture, and spring 20 means for effecting the engagement of the said arm and said plug in the disc notches and spindle recess respectively on the aligning of the notches one with the other and with the said slotted aperture, said spring means being adapted to move the plug out of alignment with the spindle recess on its disengagement therefrom under inward pressure on the plug arm.

3. A door locking device comprising, a knob divided into an inner part and an outer part detachably connected together, said inner and outer parts having a concentric annular recess and a transverse slot in their inner faces respectively and the inner part having a slotted aperture on one side of the annular recess, a plurality of discs mounted in the said annular recess in frictional contact with the wall thereof each having an outer peripheral notch and a plurality of unequally spaced inner peripheral 30 projections, a spindle on which said knob is rotatably mounted recessed in its inner end and extending at its inner end through said annular recess and said discs, a key carried by said spindle with which predetermined disc 35 projections contact when the knob is moved in opposite directions alternately whereby the disc notches are brought into alignment one with the other and with the inner part slotted aperture, a plug carried in the outer part slot out of alignment with the spindle recess having an arm extending through the slotted aperture of the inner part, and spring means for effecting the engagement of the said arm and said plug in the disc notches and spindle recess respectively on the aligning of the notches one with the other and with the said slotted aperture.

4. A door locking device comprising, a knob divided into an inner part and an outer part detachably connected together, said inner and outer parts having a concentric annular recess and a transverse slot in their inner faces respectively and the inner part having a slotted aperture on one side of the annular recess, a plurality of discs mounted in the said annular recess in frictional contact with the wall thereof each having an outer peripheral notch and a plurality of unequally spaced inner peripheral 60 projections, a spindle on which said knob is rotatably mounted recessed in its inner end and extending at its inner end through said annular recess and said discs, a key carried by said spindle with which predetermined disc 65 projections contact when the knob is moved in opposite directions alternately whereby the disc notches are brought into alignment one with the other and with the inner part slotted aperture, a plug carried in the outer part slot out of alignment with the spindle recess having an arm extending through the slotted aperture of the inner part, and spring means for effecting the engagement of the said arm and said plug in the disc notches and spindle recess respectively on the aligning of the notches one with the other and with the slotted aperture, said spring means being adapted to move the plug out of alignment with the spindle recess on its disengagement therefrom under inward pressure on the plug arm, and a follower member abutting the plug movable with the latter as it is moved into or out of alignment with the spindle recess.

tions, a spindle on which said knob is rotatably mounted recessed in its inner end and extending at its inner end through said annular recess and said discs, a key carried by said spindle with which predetermined disc 70 projections contact when the knob is moved in opposite directions alternately whereby the disc notches are brought into alignment one with the other and with the inner part slotted aperture, a plug carried in the outer part slot out of alignment with the spindle recess having an arm extending through the inner part slotted aperture, and spring 75 means for effecting the engagement of the said arm and said plug in the disc notches and spindle recess respectively on the aligning of the notches one with the other and with the said slotted aperture, said spring means being adapted to move the plug out of alignment with the spindle recess on its disengagement therefrom under inward pressure on the plug arm.

5. A door locking device comprising, a knob divided into an inner part and an outer part detachably connected together, said inner part and said outer part having a concentric annular recess and a transverse slot in their inner faces respectively, and the inner part having a slotted aperture on one side of the annular recess, a plurality of discs mounted in the said annular recess in frictional contact with the wall thereof each having an outer peripheral notch and a plurality of unequally spaced inner peripheral 90 projections, a spindle on which said knob is rotatably mounted recessed in its inner end and extending at its inner end through said annular recess and said discs, a key carried by said spindle with which predetermined disc 95 projections contact when the knob is moved in opposite directions alternately whereby the disc notches are brought into alignment one with the other and with the slotted aperture of the inner part, a plug carried in the outer part slot out of alignment with the spindle recess having an arm extending through the inner part slotted aperture, spring means for effecting the engagement of said arm and said plug in the disc notches and spindle recess respectively on the aligning of the notches one with the other and with the slotted aperture, said spring means being adapted to move the plug out of alignment with the spindle recess on its disengagement therefrom under inward pressure on the plug arm.

6. A door locking device comprising, a knob divided into an inner part and an outer part detachably connected together, said inner and outer parts having a concentric annular recess and a transverse slot in 100

- their inner faces respectively and the inner part having a slotted aperture on one side of the annular recess, a plurality of discs mounted in the said annular recess in frictional contact with the wall thereof each having an outer peripheral notch and a plurality of unequally spaced inner peripheral projections, a spindle on which said knob is rotatably mounted recessed in its inner end 5 and extending at its inner end through said annular recess and said discs, a key carried by said spindle with which predetermined disc projections contact when the knob is moved in opposite directions alternately whereby the disc notches are brought 10 into alignment one with the other, a plug carried in the outer part slot out of alignment with the spindle recess having an arm 15 extending through the inner part slotted aperture, said arm having a notch intermediate its length, a follower member abutting the plug seated in the outer part slot having an arm extending slidably through 20 the outer part wall, and a spring disposed in the outer part slot secured at midlength to the plug having on one side a substantially U-shaped portion the free end of which is engaged in the said arm notch 25 while on its other side it is designed to press on the follower arm, said spring being adapted to effect the engagement of the plug arm and plug in the disc notches and the spindle recess respectively on the aligning 30 of the notches one with the other and with the slotted aperture and to move the plug out of alignment with the spindle recess on its disengagement therefrom under inward pressure on the plug arm.
- 40 7. A door locking device comprising, a knob divided into an inner part and an outer part detachably connected together, said inner and outer parts having a concentric annular recess and a transverse slot in 45 their inner faces respectively, a plurality of discs mounted in said recess each having an outer peripheral notch and a plurality of unequally spaced inner peripheral projections, spring fingers secured to the wall of 50 the recess bearing on the peripheries of the discs there being one finger for each disc whereby they are maintained in frictional contact with the recess wall, a spindle on which said knob is rotatably mounted recessed at its inner end and extending at its 55 inner end through said annular recess and said discs, a key carried by said spindle with which predetermined disc projections contact when the knob is moved in opposite directions alternately whereby the disc notches 60 are brought into alignment one with the other, a plug carried by the outer part slot engageable in the spindle recess on the aligning of the disc notches, and means for disengaging the plug from the recess. 65
8. A door locking device comprising, a knob, a spindle on which said knob is freely and rotatably mounted, means within the knob for engaging the knob and spindle so as to operate together, and combination 70 means within the knob controlling such engagement, said means being in frictional contact with the knob and only operative to effect the combination on partial rotation of the knob under pressure insufficient to 75 overcome said frictional contact.
9. A door locking device comprising, a knob, a spindle on which said knob is freely and rotatably mounted, means within the knob for engaging the knob and spindle so as to operate together, combination means 80 within the knob controlling such engagement, said means being in frictional contact with the knob and only operative to effect the combination on partial rotation of the 85 knob under pressure insufficient to overcome said frictional contact, and means for indicating the required amount of such partial rotation.
10. A door locking device comprising, a 90 knob, a spindle on which said knob is rotatably mounted, and combination-controlled means within the knob for operatively connecting it to the spindle including a key removably seated in the spindle capable 95 of being transposed from a longitudinal position on the spindle to an angular one whereby the range of possible combination changes is amplified.

Dated at Vancouver, B. C., this 21st day of May, 1923.

CHRISTIAN PHILIP SHINDLER.
